PRESSURE REGULATOR

Adoniram J. Green, West Caldwell, N. J., assignor
to General Electric Company, a corporation of
New York

Application November 19, 1932, Serial No. 643,469

12 Claims. (Cl. 200—83)

My invention relates to improvements in pressure-regulators, more particularly to improvements in pressure-regulators having a switch mechanism therein.

It is generally an object of my invention to provide a pressure regulator of the above type in which the construction is simplified and which is capable of quick and ready assembly. It is a further object of my invention to improve the switch mechanism of the above type regulator to prevent single phasing of the electric motor being controlled by obtaining simultaneously a good wiping action of the movable contacts. It is also an object of my invention to provide a pressure regulator of the above type having an unloader valve which may be operated directly by the switch mechanism in response to pressure variations or manually, the manual means being capable of operating both the switch mechanism and the unloader valve independently of the pressure-responsive mechanism.

In the preferred embodiment of my invention I provide a pressure regulator having a casing. In two sides of the casing apertures are provided for maintaining a contact-supporting element of the switch mechanism fixedly in position and for pivotally supporting a movable portion of the switch mechanism, whereby the entire switch mechanism may be supported by the sides of the casing when assembled, thus eliminating supporting brackets, nuts and bolts. The pressure-responsive mechanism for operating the switch mechanism is supported on a third side of the casing and comprises a resilient diaphragm supported adjacent to an opening in the side of the casing through which a lever-operating mechanism extends and moves with the diaphragm. Opposing the action of the diaphragm is a spring member. A fixed member, the only one necessary within the casing, supports this spring, and a lever mechanism which is responsive to the action of the pressure-responsive diaphragm and is connected to the switch mechanism for operating the same with a snap action. This operating connection comprises a spring and pivoted lever which brings about a snap action which will be described.

The movable portion of the switch mechanism includes a movable member, carrying one or more hollow switch-arm supporting devices made of insulating material. The switch arm is not fastened to the hollow member but is loosely inserted and maintained therein by means of a spring. Relative movement can, therefore, take place between the switch arm and the supporting

member when the switch is moved to a closed position. In action, this unique construction results in a good wiping action between the switch arm and the contacts carried by the fixed member.

The unloader valve, which has the function of reducing the pressure in the compressor discharge piping to facilitate starting the compressor motor, is mounted on the side of the casing. An arm carried by the movable member of the switch mechanism extends through the side of the casing and operates the unloader valve when the switch opens. A push rod is provided for manually opening the pressure switch and operating the unloader valve independently of the action of the pressure mechanism. A locking feature is provided on this push rod whereby the switch may be locked in the open position.

A better understanding of my invention will be obtained by referring to the attached drawing in which Fig. 1 shows a cross section of my pressure regulator, taken through the center of Fig. 2; Fig. 2 shows an end view thereof; Fig. 3 shows a top view of my pressure regulator; Fig. 4 shows an exploded view of the pressure regulator; Fig. 5 shows a detailed section view of a portion of the movable part of the switch mechanism; and Fig. 6 shows a view of the unloader valve partly in cross section, and the plunger for manually operating the unloader valve and pressure-operated switch.

Referring to Figs. 1, 2, 3 and 4, the casing has the sides 10, 10' and 11, bottom 12' and is provided with a cover 11'. The sides 10 and 10' and bottom 12' are of one piece and are bent into a U shape when the casing is formed. The side 11 and the cover 11' are separate pieces. The side or side wall 11 and parts of the switch mechanism are maintained in place when the piece comprising the sides 10, 10' and bottom 12' is formed into the U shape to provide the casing for the pressure regulator. Apertures such as 32 and 33 (see Figs. 1 and 4) are provided in the sides and bottom into which portions of the side 11 project to maintain the side 11 in place. The side 11 has an inwardly flared opening 12 therein. Mounted over this opening and spaced therefrom by means of the spacer 14 is the resilient diaphragm 15, preferably of rubber, although this may be of some other material. The diaphragm 15 and the spacer, diaphragm and plate are secured to the casing concentric with flared opening 12 by means of the screws 17.

A substantially U-shaped member 18 is mount-

ed opposite the opening 12 within the casing and is fastened to the side 11 of the casing by means of screws 19 and 20, as shown in Fig. 2. This U-shaped member pivotally supports the lever 23, as shown in Figs. 1 and 2, by means of the pivots 21 and 22. A member 41 engages the diaphragm 15 and supports a cup-shaped member 40 by means of the pin 41'. This cup-shaped member, more clearly shown in Fig. 4, is provided with arms such as 42 and 42' pivotally connected to the lever 23 by means of the pivots 43 and 43'. Supported within the cup-shaped member 40 is a spring 46, the compression of which can be varied to permit operation at any desired pressure value by means of the nut 45 supported on the screw member 44 having its shouldered head abutting the cross-portion of the U-shaped fixed member 18. It will be observed, therefore, that the spring 46 opposes movement of the diaphragm 15 to operate the lever 23 by means of the cup-shaped member pivoted thereto. This portion of the pressure regulator may be termed the pressure-responsive mechanism for operating the switch which is mounted in the top part 25 of the casing.

The switch comprises a fixed member supporting contacts and a movable member supporting the switch arms cooperating with the contacts. The member 39 is made of insulating material 30 and is supported by means of the sides 10 and 10' of the casing within the apertures 50 and 51. This contact-supporting member 39 is provided with partitions 39' for separating the supporting member into compartments as is clearly shown in Figs. 2, 3, and 4. The contact-supporting elements 38' are U-shaped and are fastened to the contact support by means of screws. These contact-supporting members have fastened thereto the contacts 38.

The movable part of the switch mechanism includes a frame 28 pivotally mounted, as shown in Fig. 3, at 29 and 30. In order to assemble the pressure regulator, the sides of the casing are sprung to permit insertion of the contact-carrying member and the movable portion of the switch mechanism. The casing is then held together by means of the assembly bolt 52 and nut 53. This eliminates extra supports in the casing. The movable frame 28 has fastened thereto by means of screws such as 35, the hollow switch-arm supporting members 33 and 34 which are of insulating material. These members are identical.

Referring to Fig. 5, it will be observed that the switch arm 31 having a contact 37 thereon is loosely inserted within the hollow member 33 and maintained therein by means of a torsion spring 37' cooperating with the depression 33' in the hollow member and the small opening 31' in the switch arm. The portion 33' has therein the opening 31' for permitting insertion of the screw 35, whereby the hollow member may be maintained fixedly upon the frame 28. The frame 28 has extending therefrom the arm 36 which protrudes through a curved aperture in the side 10' of the casing to engage the unloader valve mechanism.

The movable frame 28 carrying the switch arms 31 and 32 is moved to engage and disengage the switch arms from the contacts upon movement of the lever 23 through the agency of the U-shaped member 26 pivoted to the upper end 24 of the lever 23 and the over-center spring 27 connecting the member 26 and the frame 28. The spring 27 engages in the small opening 28'

in the frame 28, as shown in Figs. 1, 2, and 3. The detailed operation of the switch by the lever mechanism in response to movement of the diaphragm 15 will be described in detail below.

The unloader valve, shown in Fig. 6, is mounted 5 on the side 10' of the casing. It includes the brackets 54 and 55 which are fastened to the side of the casing 10' by means of screws 56. The bracket 54 has an arm 57 thereon pivotally supporting the lever 58. The valve proper is supported by bracket 54 by means of the nuts 59 and 59' which engage the threaded extension 60 of the valve. The valve proper has an inlet 61 thereto and an outlet 62. The piston 63 is biased to closed position by means of the spring 64 which is held in place by a screw 64' having an opening therethrough. The piston is moved by means of a rod 65 connected therewith whenever lever 58 is depressed. This may be done by means of the projecting arm 36 mounted on the frame of the switch mechanism or by means of the manually operated plunger 66. This plunger is maintained biased in an upward position by means of the spring 67 acting against the pin 68 carried by the plunger. When the plunger 25 66 is depressed, it engages both the arm 36 and the lever 58 to open the switch and to operate the valve. The pin 68 carried by the plunger 66 cooperates with a portion of the frame 55 having the slot 69 therein. It will be observed that if 30 the plunger 66 is depressed and rotated in a counter-clockwise direction, that the pin 68 will engage the horizontal portion of the slot 69 and maintain the plunger in the depressed position against the bias of the spring 68. 35

The detailed operation of my pressure regulator follows: Assuming the parts to be in the position shown in Fig. 1, which shows the switch in closed position, an increase in pressure on the diaphragm 15 on the side opposite from the cup-shaped member will force the members 41, cup-shaped member 40 having the arms 42 and 42' thereon, to the left against the compression in the spring 46. This will rotate the lever 23 about its pivots 21 and 22 in a counter-clockwise direction. As it does so, the pivot point of the U-shaped member 26 supported in the arms 25 and 25' carried by the lever 23 will be moved to the left, forcing the end of the U-shaped member down and increasing the tension in the spring 27. The tension in the spring 27 will be increased as the member 26 approaches a plane parallel to that of the spring. When the pivot point of the U-shaped member 26 has passed to the left of the parallel plane due to the tendency of the spring 55 to shift or move to relieve the tension therein, it will cause rotation of the frame 28 about its pivots 29 and 30 in a clockwise direction to disengage the switch arms from the stationary contacts with a snap action. As it does so, the arm 36 60 carried by the frame 28 will engage the lever 58 to operate the piston rod 65 to open the valve so that the compressor being controlled can exhaust to atmosphere. As the pressure in the storage tank decreases, the pressure on the diaphragm 15 will decrease permitting it to move to the right under the action of the spring 46. The lever is rotated in a clockwise direction and the spring is again put under increased tension until 65 the member 26 passes to the right of the parallel plane, passing through the U-shaped member and the spring. The spring will then rotate the frame member 28 in a counter-clockwise direction to close the switch members 31 and 32 70 75

on the contacts 38, the member 26 being limited in its movement by the stop 26'.

It will be observed that as the switch arms carrying the contacts 31 engage the contacts 38 carried by the stationary contact-carrying member, a wiping action will result since the relative movement between the switch carrying hollow members 33 and the switch arm 31 is permitted due to the loose connection between these two members, the frame moving the hollow members past the point at which the contacts on the switch members and the stationary contacts engage. The angular displacement of frame 28 about pivots 29 and 30 is limited to the amount necessary for desired action by properly proportioned projections 80 and 81 of frame 28 engaging with part 11 of the casing.

It will further be observed that the action thus described of increased tension in the spring 27 during the operating sequence prevents a decrease of contact pressure between contacts 37 and 38 while they engage each other.

The operation of the manually operated plunger for opening the switch and operating the unloader valve was described above.

It will be observed that by means of my construction I have eliminated a number of parts heretofore considered necessary in connection with the mechanism between the diaphragm and the switch mechanism. I have also simplified the construction and the assembly thereof, and have provided a switch of simple design insuring proper wiping when the switch is closed. In addition, I have provided a manual release for the unloader valve and the switch mechanism.

The embodiment of the invention illustrated and described herein has been selected for the purpose of clearly setting forth the principles involved. It will be apparent, however, that the invention is susceptible of being modified to meet the different conditions in its use, and I, therefore, aim to cover by the appended claims all modifications within the true spirit and scope of my invention.

What I claim as new and desire to secure by Letters Patent of the United States, is,—

1. A pressure regulator having a casing, a switch mechanism mounted within said casing, a lever operatively connected with said switch mechanism, a substantially U-shaped member fixed within said casing and pivotally supporting said lever thereon on opposite sides thereof, a diaphragm responsive to varying pressures mounted on a side of said casing, and an operating member associated and movable with said diaphragm, said operating member having a cup-shaped portion with oppositely disposed arms extending therefrom and engaging said lever adjacent its pivotal supports, and an adjustable resilient member supported by said U-shaped member and by said operating member within the cup-shaped portion thereof for opposing operation of said lever by said diaphragm in response to varying pressures.

2. A pressure regulator including a casing having a side wall, a diaphragm mounted on said side wall, an operating member operatively associated with said diaphragm, a U-shaped member having a cross portion and legs secured to said side wall on opposite sides of said diaphragm, a compression spring one end of which is supported by said cross portion and the opposite end of which is supported by said operating member, circuit control means, a lever movable between predetermined positions to operate said control means to

open and close a circuit, and means connecting said lever to said U-shaped member and to said operating member whereby said lever is moved between said predetermined positions by said diaphragm and said compression spring.

3. A pressure regulating mechanism including a casing having sides with oppositely disposed apertures therein, a member carrying contacts adapted to be inserted within said apertures to be supported within said casing, a switch arm mounted in the sides of said casing and co-operating with the contacts on said member, a lever mechanism mounted on another side of said casing within said casing and having connections to said switch arm for producing snap action of the same, and means responsive to pressure conditions for operating said lever mechanism to move said switch arm, said switch arm including a hollow member formed of insulating material, a switch element carrying contacts movably mounted in said hollow member and insulated thereby from said lever mechanism, and a spring for resiliently maintaining said switch element within said hollow member at one side thereof and providing for relative movement between said switch element and said hollow member when said switch element is closed upon the contacts carried by said contact carrying member.

4. In a pressure operated switch mechanism, a contact-supporting member having compartments thereon, pairs of contacts on said member mounted in said compartments, hollow support members formed of insulating material, switch arms resiliently mounted in said hollow members and cooperating with said contacts for bridging each pair of contacts, and means for operating said hollow members to engage and disengage simultaneously said switch arms from said contacts, said resilient mounting of said switch arms insuring a wiping action as said contacts are engaged and disengaged.

5. In a pressure operated switch mechanism, a member having a pair of contacts thereon, a movable member mounted in said casing, a hollow switch-arm support of insulating material carried by said movable member, a switch arm loosely mounted in said hollow member and resiliently retained therein, whereby said switch arm and hollow member may have relative movement, said switch arm having movable contacts cooperating with the contacts carried by said first member for bridging said contacts when said switch arm is moved into engagement therewith, the contacts on said switch arm providing a wiping action when moved into and out of engagement with said pair of contacts and means for operating said movable member carrying said hollow member and said movable contacts into and out of engagement with said pair of contacts.

6. In a pressure-regulating device having a casing, a member supported by opposite sides of said casing and carrying pairs of contacts thereon, said member having ribs between each of said pairs of contacts and said sides of said casing, a movable member, hollow switch-arm supporting members formed of insulating material and mounted thereon, switch elements resiliently retained within said hollow members, a lever mounted in said casing and operatively associated with said movable member, pressure-responsive means carried by said casing and operatively connected with said lever for moving said switch elements into contact with said pairs of contacts to bridge said contacts and out of contact there-

with, and resilient means for opposing operation of said lever by said pressure-responsive means when said pressure responsive means moves in response to pressure variations, said hollow members electrically insulating said pressure-responsive means from said switch elements.

7. A pressure regulator mechanism having a casing including a single U-shaped portion providing oppositely disposed sides and a bottom 10 for said casing, said sides having oppositely disposed apertures therein, a member carrying contacts and a movable switch member cooperating therewith adapted to be inserted within said apertures and supported by said sides when said 15 sides are sprung to permit insertion of said members within said apertures, said sides and bottom having other apertures and a third side supported in said other apertures and supporting a pressure-responsive mechanism for operating 20 said movable switch member to engage and disengage the contacts carried by said contact-carrying member.

8. A switch mechanism including a fixed member having contacts thereon, a hollow member 25 formed of insulating material, movable means supporting said hollow member, a switch arm having contacts thereon loosely mounted in said hollow member, a torsion spring within said hollow member, one end of said spring being mechanically interlocked with said hollow member 30 and the opposite end of said spring being mechanically interlocked with said switch arm to retain said switch arm within said hollow member, said hollow member being formed to provide 35 relative movement between said switch arm and said hollow member when said switch arm is closed upon the contacts carried by said contact-carrying member.

9. In a pressure regulating device having a 40 casing, a member formed of insulating material supported by opposite sides of said casing and carrying pairs of contacts thereon, said member having ribs between each of said pairs of contacts and between said contacts and said sides 45 of said casing, a movable member supported by said sides, hollow supporting members formed of insulating material and mounted on said movable member intermediate each pair of said contacts, a switch element arranged to nest within each of 50 said hollow supporting members and having a contact portion for bridging a pair of said contacts, resilient means in each of said hollow supporting members retaining each switch element in said nesting relation and providing for a wiping action between said contact portion and said 55 pair of contacts, a lever operable between said hollow supporting members and resilient means connected to said movable member and to said lever for operating said switch elements with a snap action into and out of engagement with 60 said pairs of contacts, said hollow supporting members electrically insulating said elements one from the other and from said resilient means and said lever.

65 10. A pressure regulating device comprising a casing, a movable switch member pivotally supported by opposite sides of said casing, a pair of hollow supporting members formed of insulating material and secured in spaced relation to said movable member, a pair of bridging contact members provided with shanks arranged to nest respectively within said hollow supporting members, a torsion spring mounted within each of said hollow supporting members one end of said torsion spring being mechanically interlocked with

its associated hollow member and the other end of said spring being mechanically interlocked with its associated bridging member to retain said bridging members within said hollow members and to provide for relative movement of said 5 bridging members with respect to said hollow members, two pairs of stationary contacts supported from said sides of said casing adjacent to said bridging members, a switch operating lever movable between said pair of hollow members and an over-center spring connected at one end to said movable member and at its opposite end to said operating lever to operate in response to movement of said lever, said hollow members with a snap action into and out of engagement 15 with said stationary contacts, said hollow members electrically insulating said bridging contact members from said switch lever, said movable member and said over-center spring.

11. In combination, a pressure regulating device provided with a casing and a diaphragm mounted on one wall of the casing, of a U-shaped member, the respective legs of which are secured to said wall on opposite sides of said diaphragm, an adjustable compression spring one end of 25 which is supported by said U-shaped member, a cup-shaped member supporting the opposite end of said compression spring and biased by said compression spring against said diaphragm, a switch operating lever pivotally supported by said 30 legs of said U-shaped member, connections between said cup-shaped member and said operating lever for moving said lever between predetermined positions in response to movements of said cup-shaped member by said diaphragm and said 35 spring, a pivoted switch member supported by said casing, a pair of hollow support members formed of insulating material mounted on said pivoted member and extending on opposite sides of said switch member and between said predetermined 40 positions of said operating lever, a pair of bridging contacts mounted in said hollow members, torsion springs mounted within said hollow members for retaining said bridging members within said hollow members and providing 45 for relative movement of said bridging members with respect to said hollow members, and a resilient operating connection between said switch member and said pivoted member for operating said hollow members between open and closed 50 circuit positions.

12. A pressure regulator comprising a U-shaped member forming side walls and a bottom wall of a casing, a removable side wall interconnected with said U-shaped member, two pairs of stationary contacts, a stationary member formed of insulating material for supporting said pairs of contacts, said side walls being provided with apertures for supporting the ends of said stationary member, a switch member pivotally 55 mounted on said side walls, hollow supports formed of insulating material secured to said switch member in spaced relation with each other, bridging contact members extending substantially at right angles to said pivoted member and nesting within said hollow supports, torsion springs resiliently retaining said bridging members 60 within said hollow supports and providing for relative movement of said bridging members with respect to said supports, a switch operating lever provided with an extension movable between said hollow supports, resilient means interconnecting said switch member and said operating lever, a U-shaped member secured to said 65 70 75

removable side wall and pivotally supporting said switch lever, a cup-shaped member pivotally secured to said switch operating lever, a pressure responsive diaphragm mounted on said removable wall for moving said cup-shaped member and said lever from one position to a second position to cause operation of said bridging contact

members by said resilient means, and a compression spring one end of which nests within said cup-shaped member and the other end of which is supported by said U-shaped member for operating said cup-shaped member and said lever from said second position to said first position.

ADONIRAM J. GREEN.
